CLAIM

The ornamental design for a BASE FOR VIDEO GAME CONSOLE, as shown and described.

DESCRIPTION

FIG. 1 is a perspective view of the base for video game console;

FIG. 2 is a front view of the base for video game console;

FIG. 3 is a rear view of the base for video game console;

FIG. 4 is a left side view of the base for video game console;

FIG. 5 is a right side view of the base for video game console;

FIG. 6 is a top view of the base for video game console; and

FIG. 7 is a bottom view of the base for video game console.

The broken lines showing portions of the base for video game console form no part of the claimed design.
